UNITED STATES PATENT OFFICE.

JACOB E. NEAHR, OF NEW YORK, N. Y.

MATCH HOLDER.

1,413,991.

Specification of Letters Patent. Patented Apr. 25, 1922.

Application filed January 31, 1918. Serial No. 214,592.

To all whom it may concern:

Be it known that I, JACOB E. NEAHR, a citizen of the United States, residing in the city, county, and State of New York, have invented certain new and useful Improvements in Match Holders, of which the following is a specification.

This invention relates to match-safes of the kind illustrated in Patent No. 1,122,791, granted to me December 29, 1914, in which a coil of match-igniting strip is placed in a drum, the leading end of the strip being led out through an aperture in the side of the drum, and the strip being wound once around the drum and then secured, thus producing a match-striking device, since the strip is supported by the wall of the drum at the match-striking operation. In said patent the drum is surmounted by a match-safe.

One of the objects of the present invention is to simplify and improve the construction disclosed in said patent, particularly with a view to rendering the device more compact, as well as to reducing the cost thereof; and one of the objects in rendering the device more compact is to produce a combined match-safe and igniter of symmetrical design and pleasing proportions.

Instead of surmounting the coil and drum by a match-safe, as in said patent, I use a coil which is in the form of an annulus having a large central opening within which the matches stand. Said opening in the coil serves as a part of the match-holding portion of the safe. The upper part of the safe may be in the form of an annular cap which surmounts the drum, said cap having a tubular or other flange which extends down within the coil and constitutes the inner wall of the match-safe. Hence, the height of the match-safe and coil combined need be no greater than the height of an ordinary match-safe alone. This produces a symmetrical and pleasing appearance, while the advantage is retained of a rigid backing as a support for the exposed ignition-strip at the match-striking operation. Said flange divides the match-safe into an outer annular compartment to confine the coil, and an inner compartment to confine the matches; said outer compartment having an annular removable cap or closure which leaves the inner compartment open.

The match-safe is illustrated as carried upon a pedestal, from which rises a dished

base, said base itself forming the cover or lid of an ash receptacle, as set forth in my pending application No. 208,222, filed December 21, 1917 (now Patent No. 1,334,961, dated March 30, 1920). 60

Other features and advantages will hereinafter appear.

In the accompanying drawings,

Figure 1 is a central sectional elevation of the preferred form of my improvements, 65 showing match-safe, coil, drum, ash receptacle and bell.

Figure 2 is a plan of the open drum and coil, showing the central bell-striking rod in cross-section. 70

Figure 3 is a perspective of the drum and clip. 75

Figure 4 is a sectional detail illustrating the manner of locking the clip in strip-clamping position. 75

The coil 10 of ignition-strip may be like that set forth in said Patent No. 1,122,791, except that it is made in the form of a ring of very large diameter, thus leaving a large opening within which the matches may find room as they rest upon the floor of the drum which contains said ring. The matches 12 are confined by a tubular flange 13 formed upon a cap 14 which is detachably mounted upon the drum 15 which contains the coil; 80 said flange extended down sufficiently to form the inner wall of the match-safe, and this wall 13 occupying a position within the coil 10, so that the floor 16 of the drum and the wall 18 form a complete receptacle for 90 the matches. The device presents the appearance of a match-safe of moderate height supported upon a pedestal 17, which may rise from a base 18 which is preferably dished at 19 to form a temporary holder for 95 cigar-ashes, burnt matches, etc.; the match-safe being very compact and not substantially increased in size by reason of the addition of the surrounding ignition-coil. The height may be further diminished by extending the lower portion 20 of the match-safe within the pedestal 17, so that the lower ends of the matches 12 stand within the pedestal, which may be short, as illustrated. The compartment or portion 20 is of box 100 form having preferably a heavy metal disk or floor 20^a to give weight to the structure; and the annular floor 16 of the drum may extend out from the top of the box portion 20; or the drum may be regarded as an en- 110

largement of the box, or the box may be viewed as a central depression in the floor 16 of the drum, which completes the match-safe whose wall is the tubular flange 13.

- 5 The coil 10, which may be wound upon a hollow core 21, is placed within the drum 15, and one end is led out through an aperture 22 in the side of the drum. Then the cap 14 is forced down upon the drum, said 10 cap comprising, besides said flange 13, an outwardly and downwardly flaring portion, which at its lower edge is beaded and rolled inwardly at 23 to fit upon the drum, the latter having at intervals rounded nipples 24 15 struck out therefrom, over which the edge of the cap catches, whereby the cap is releasably locked upon the drum; two of said nipples being in the vicinity of said aperture 22 in the wall of the drum, where said wall is 20 slightly yielding. The flaring or beaded portion 23 of the cap extends considerably outside of the wall of the drum, and corresponds with a flange 25 formed at the bottom of the drum, so that the end of the strip 25 which is wound around the drum at 26 is confined between these upper and lower flanges, whereby it is protected from injury as well as confined against upward or downward displacement.
- 30 When the strip is led out through the aperture 22, it may be wound around the drum and then secured by a finger 27 which is erected upon a lever 28, pivoted at 29, between its ends, to the bottom of the drum, one 35 end of the lever forming a compressible finger-piece 30 projecting beyond the edge of the drum, so that by pressing the finger-piece inwardly, the lever may be swung and the clip 27 released or retracted from the drum.
- 40 Thus by pressing upon the finger-piece at one end of the lever, the clip may be released, while, by pressing upon the clip at the other end of the lever, it may be closed upon the ignition-strip, and may be held 45 releasably locked in such position by means of co-operating nipples 31 and 32, one upon the lever and one upon the bottom of the drum.

One of the objects of the invention is to 50 anchor or steady the safe at the match-striking operation, even though it is mounted upon a cover or lid which is removable from the main receptacle 43, and even though the entire device has little weight. To this 55 end the receptacle is made broad or of great diameter, to afford an ample base, and the match-safe is sunken or lowered to nearly the level of the cover 18, this lowering being effected by setting the match-safe down with 60 in the short pedestal 17 which rises from the dished-out portion 19 of the cover or tray, and the latter is interlocked with the rim of the receptacle 43 all around the latter. Hence on whatever side of the match-safe 65 a match is struck, the receptacle 43 remains

unmoved, and the cover 18 remains in place thereon.

The bell-mechanism, which may be omitted if desired, may comprise a stem 33 mounted by a button 34 and extending up through the center of a match-safe, and guided at its lower portion to slide up and down in a boss 35 provided in the bottom of the match-safe. Preferably said boss is formed upon said disk 20^a which forms the 75 floor of the match-safe, said disk forming a weight, which is a desideratum in connection with a match-safe and base formed of light sheet-metal, as in the present instance. This stem extends down through the bottom 80 of the drum to operate the bell-hammer 36, and may be provided with a stop 37 for limiting its stroke, which stop may play in a slot 38 formed in a boss 39 extending down from said disk 20^a.

Said stem when depressed by means of the button 34, strikes a central rod 40 which is mounted to slide up and down in a boss 41, which is fixed upon the lower portion of a receptacle comprising a floor 42 and 90 side walls 43, which receptacle is closed by the dished base above described, as set forth in said application No. 208,222. The central portion of the floor of said receptacle is raised at 44 to make a recess, in which is 95 inserted a bell 45, and said boss 41 extends up from said raised portion 44 of the floor, and contains a compression spring 46, which lifts or restores the rod 40 and stem 33 when the hand is lifted from the button 34. This 100 rod 40 at its lower end strikes an arm 47 extending from the pivoted gravity hammer 36, which is swung against the bell 45 at the depression of the stem and rod. The hammer may be pivoted in an ear 48 pendent 105 from the raised portion 44 of the floor; and the bell may be carried upon a bracket 49 which is also pendent from said raised floor.

Variations may be resorted to within the scope of the invention, and portions of the 110 improvements may be used without others.

Having thus described my invention, I claim:

1. The combination of an annular coil of ignition-strip, and a drum having inner and 115 outer walls between which said coil is confined, said coil occupying the outer portion of the floor of the drum, the outer wall having an aperture through which the strip may be led, and said drum provided in 120 interiorly of said coil with a central depression in its floor to afford a match-rest and complete a match-safe.

2. The combination of an annular coil of 125 ignition-strip, and a drum having a cap or closure, said drum having a floor upon which both the coil and the matches rest, and also having inner and outer walls between which said coil is confined, said closure displaceable to afford access to the coil, said 130

inner wall integral with said closure, and said drum having in its outer wall an aperture through which the coil may be led.

3. The combination of an annular coil of ignition-strip, and a drum having a cap or closure, said drum having inner and outer walls between which said coil is confined, and a floor upon which the coil rests, said closure displaceable to afford access to the coil, said inner wall permanently fixed to said closure, and said drum having in its outer wall an aperture through which the coil may be led, and the floor of said drum also provided with a central depression to afford a match-rest and complete a match-safe.

4. The combination of an annular coil of ignition-strip, a drum having a cap or closure, said drum having inner and outer walls between which said coil is confined, said closure displaceable to afford access to the coil, and said drum having in its outer wall an aperture through which the coil may be led, and said drum also provided with a central depression to complete a match-safe, and a base having a pedestal within which said central depression extends.

5. The combination of a drum having a coil-supporting floor and having an aperture in its outer wall, said drum also having an inner wall spaced from the outer wall, and also having means to close the space between said walls, said closing means being movable to afford access to said space, and said drum having a central depression in its floor to afford a rest for the matches and complete a match-safe.

6. The combination of a drum having an aperture in its side wall, a cap for said drum, said cap having an integral interior flange extended downwardly therefrom and open at its bottom to confine matches inserted in the drum, whereby a match-safe is provided, and an annular coil of ignition-strip confined between said extended flange and said side wall of the drum, and resting upon the floor of the drum, said floor also affording a support or rest for the matches.

7. The combination of a drum having an aperture in its side wall, an annular coil of ignition-strip confined within said drum and resting upon its floor, and an annular cap for said drum, said cap having an interior permanent flange extended downwardly therefrom within said coil and open at its bottom, and said drum having a central depressed portion in its floor within said coil, to receive and support matches which are confined by said flange.

8. The combination of a box having a bottom portion to confine the lower ends of standing matches, said bottom portion comprising a floor on which the matches stand, said box also having an enlarged upper portion to form a drum to receive an annular

coil of ignition-strip, said floor depressed below said drum, and said drum having an aperture through which the strip may be led, and means to cover the strip, said covering means movable to give access to the 70 coil.

9. The combination of a box having a bottom portion provided with a floor portion to support and confine the lower ends of standing matches, said box also having an enlarged upper portion to form a drum having a floor portion to receive an annular coil of ignition-strip, said drum having an aperture through which the strip may be led, means to cover the strip, said covering means 75 movable to give access to the coil, and means to extend within the coil and terminating above the first floor portion to form the upper portion of a match-safe.

10. The combination of a box having in 80 its side walls an outwardly extending floor portion to form a seat or rest for an annular ignition coil, and being of enlarged transverse dimension above said seat, to receive the coil, and being surmounted by an annular closing device, said box comprising a lower portion comprising a match floor 85 which is depressed below said seat.

11. The combination of a box having in 90 its side walls an outwardly extending floor portion to form a seat or rest for an annular ignition strip coil, and being of enlarged transverse dimension above said seat, to accommodate the coil, and being surmounted by an annular closing device, and an external bead being formed in the wall of the box at the junction of said seat and said enlarged portion of the box, and said closing device having a flange or bead extending around the box, said enlarged portion 95 of the box having an aperture through which the ignition-strip may be led, and said beads serving to confine a winding of the strip around said enlarged portion of the box.

12. A match-safe having an annular compartment for receiving an annular coil of match-igniting strip, and having a compartment within the coil for receiving matches, said annular compartment provided with an annular closing device which leaves the 110 match-receiving compartment open, said match-receiving compartment extended below the bottom of said annular compartment, and smaller in transverse dimension, the main portion of said match-receiving 115 compartment being below the top of said coil.

13. The combination of a match-safe, and a pedestal within which the lower portion of the match-safe extends, said match-safe provided with a drum within which is confined a coil of igniting material, the end portion of the coil being extended around the drum, and said parts being so arranged that the matches stand within the coil and pedestal. 120 125 130

14. The combination of a match-safe, and a pedestal within which the lower portion of the match-safe extends, said match-safe provided with a drum within which is confined 5 a coil of igniting material, the end portion of the coil being extended around the drum, and said parts being so arranged that the matches stand within the coil and pedestal, 10 said match-safe having a match-floor within the pedestal and provided above said floor with a support for the coil.
15. The combination of a match-safe, and a pedestal within which the lower portion of the match-safe extends, said match-safe provided with a drum within which is confined 15 a coil of igniting material, the end portion of the coil being extended around the drum, and said parts being so arranged that the matches stand within the coil and pedestal, 20 said match-safe having a match-floor within the pedestal and provided above said floor with a support for the coil, said drum overhanging said pedestal and being of larger diameter.
16. The combination of a match-safe, a 25 pedestal therefor, said match-safe and pedestal arranged one within the other, so that the matches stand within the pedestal, and a coil of igniting material within which the 30 matches stand, a portion of the coil being extended around the safe to afford a match-striking surface; the recited structure comprising a device to afford a support for the coil.
17. The combination of a match-safe, and a pedestal therefor, said match-safe and pedestal arranged one within the other, so that the matches in the safe stand within the 35 pedestal; said safe provided with a band of igniting material extending therearound to afford a match-striking surface.
18. The combination of a match-safe having an enlarged or drum portion to contain an annular coil of igniting material of which a portion extends around the drum to afford 45 a match-striking surface, and a pedestal, said match-safe and said pedestal so connected that matches confined in the safe stand within the pedestal.
19. A match-safe comprising a drum to contain an annular coil of ignition strip of which a portion extends around the drum to afford a match-striking surface, said drum provided with a bottom upon which the coil rests, the drum having a central depression 50 having a floor substantially depressed below the bottom of the coil, said floor forming the bottom of a receptacle to contain matches inserted within the coil; the main portion of 55 said receptacle being below the top edge of the coil, and a tubular wall inserted within the drum and supported thereby, to confine the upper ends of the matches.
20. The combination with a base in the form of a receptacle, of a cover removable 60 from said receptacle and dished to form an ash tray and provided with a pedestal or support, and a match-safe, said safe and said pedestal or support arranged one within the other, so that matches placed in the safe 65 may stand within the pedestal or support, said safe provided with match-igniting surfaces on all sides thereof, said cover formed to interlock with or catch firmly upon the brim of said receptacle all around the same, 70 to afford an anchorage or support for the safe at a match-striking operation on any side of the match-safe.

JACOB E. NEAHR.
